ANTIPERSPIRANT AND DEODORANT

Emil Klarmann and Louis W. Gates, Bloomfield,
N. J., assignors to Lehn & Fink Products Corporation, a corporation of Delaware

No Drawing. Application September 13, 1941,
Serial No. 410,759

9 Claims. (Cl. 167—90)

The present invention relates to improvements in compounds for inhibiting or retarding perspiration.

In compounds, such as solutions and creams, intended for the purpose of retarding or checking perspiration at localized areas of the skin, it has hitherto been customary to employ various astringent soluble salts of polyvalent metals of groups above the alkaline earth group, such as zinc, iron, and aluminum. Thus use has been made of the chlorides and sulfates of zinc and iron, the acetate, lactate, acetotartrate or sulfo-carbolate of aluminum, and particularly aluminum salts of strong acids, such as aluminum chloride, aluminum sulphate and the like. Such compounds are occasionally found to have local irritant action, and are also found to have a deleterious effect upon clothing with which they come in contact. These solutions of compounds of astringent salts of such metals, and particularly the salts with strong acids, when brought in contact with fabrics such as the ordinary cotton and cellulose or cellulose derivative fabrics, cause a very marked decrease in the strength of such fabrics, particularly when they are pressed or ironed, and lead to rapid deterioration or rotting of the fabric. Such difficulties arise particularly in connection with the use of creams, some portions of which tend to adhere to garments worn by the user. These garments, if pressed or ironed without careful removal of the astringent metallic salt, are greatly reduced in strength or may be practically ruined.

These solutions or creams of aluminum chloride or sulfate of the strength employed for inhibiting or retarding perspiration, for example, solutions of 10 to 20%, cause a decrease in tensile strength of cotton or cellulose fabrics of 50% or more on pressing. Approximately similar deterioration of fabrics occurs with other metallic astringent salts suitable for retarding or checking perspiration. The deteriorating effect of such compounds upon the fabric becomes an important factor in their use. Such deterioration also occurs to a considerable extent with woolen and silk fabrics.

In accordance with the present invention, it has been found that the deteriorating effect of such perspiration retarding compounds upon fabrics may be greatly reduced or substantially eliminated without affecting the efficiency of the compounds in retarding or inhibiting perspiration, by incorporating or suspending in the compound a water-insoluble basic compound of a metal, preferably one not having any decided color.

Thus, oxides, hydroxides or carbonates of zinc, magnesium or aluminum may be employed. Proportions of from about 1% to about 3% have been found to be adequate. Lower proportions may be used if desired. Larger proportions are unnecessary; and if too large a proportion is used, it may reduce the perspiration inhibiting effect of the metallic astringent salt employed.

Contrary to expectations, the water-insoluble basic compound added to the solution of astringent compound in the preferred proportions will dissolve therein. Apparently, hydrolysis of the astringent salt develops sufficient acidity to bring about solution of the insoluble basic compound, 15 probably with the formation of a complex. When in contact with fabrics and particularly at high temperatures such as are used in pressing or ironing, the small proportion of the insoluble basic compound added to the solution of the astringent compound appears to affect the latter in such a manner as to prevent it from materially injuring the fabric.

The water-insoluble basic metal compound may be introduced as such into the solution or cream 25 containing the astringent metal compound or may be formed therein by the addition of a suitable proportion of a soluble base, such as a hydroxide or carbonate. In the former case, the water-insoluble basic compound may be one of another metal than that of the astringent metallic salt, or may be of the same metal. In the latter case, it will ordinarily be a basic compound of the same metal as that of the astringent metallic salt; and when formed in this manner, the 30 insoluble basic compound may not remain in solution, but may be in the form of a precipitate which functions to inhibit fabric corrosion as described.

As an example of the results secured by the 40 use of the present invention, an astringent solution or cream containing about 17% of aluminum sulfate will bring about, at pressing temperature, a corrosion of cotton fabric indicated by a reduction in tensile strength of over 50%. By incorporating in the solution or cream about 1.7% of aluminum hydroxide by the addition of a suitable proportion of sodium hydroxide or other suitable soluble base, the resulting solution or cream will, under the same conditions, have only 45 a negligible corrosive action, as indicated by a reduction in tensile strength in the order of about 2%. The incorporation of precipitated aluminum hydroxide as such in similar amounts gives approximately similar results. The addition to such a solution or cream containing about 17% of

aluminum sulfate of a small proportion, say about 2%, of the oxide or carbonate of zinc or magnesium likewise greatly reduces the undesired corrosive action on fabrics under pressing or ironing conditions, as indicated by a loss in tensile strength in the order of 10% or less.

The results above given are illustrative of those secured with other metallic astringent salts as heretofore set forth, and with varying proportions of the astringent salt in the compound, lotion or cream. The proportions of the soluble astringent metal salt and of the water-insoluble basic salt may vary widely, as heretofore indicated. In general, effective results are secured, without reducing the anti-perspirant effect of the soluble astringent salt, if the amount of the insoluble basic salt is from about 4% to about 15% of the amount of the soluble astringent salt.

The following are illustrative embodiments of compounds prepared in accordance with the present invention. All parts indicated are by weight.

Example I

	Parts
Aluminum chloride	20
Precipitated aluminum hydroxide	2.5
Water	77.5

Example II

	Parts
Aluminum sulfate	18
Zinc oxide or magnesium oxide	3
Alcohol	10
Water	69

Example III

	Parts
Aluminum sulfate	17
"Tegacid"	15
Spermaceti	5
Sodium hydroxide	1.5
Water	61.5

Example IV

	Parts
Aluminum chloride	15
"Tegacid"	15
Spermaceti wax	3
Beeswax	2
Magnesium oxide	2.5
Water	62.5

The soluble aluminum salts in the above formulas may be replaced by other astringent aluminum salts, such as the acetate, mono-chloroacetate, lactate, acetotartrate or sulfocarboxilate, or by corresponding soluble astringent salts of zinc, iron or other polyvalent metals, such as are commonly employed to check or inhibit excessive perspiration. The sodium hydroxide may be replaced by other soluble basic salts such as the carbonates or hydroxides of the alkali metals and ammonium.

"Tegacid," as referred to herein, is the name given a trade product used as an acid emulsifying agent, and is apparently a combination of glycerol monostearate with an amino compound of high molecular weight, i. e., with a phosphoric acid derivative of an oleic acid amide of diethyl ethylene diamine. Other acid emulsifying agents may be used in its place.

Water-free creams may also be prepared in accordance with the present invention by employing suitable vehicles, such as Vaseline, lanolin and the like. The methods of preparing the solutions or creams are those commonly employed in pharmaceutical practice.

Although the invention has been described in connection with the details of certain specific examples thereof, it is not intended that these shall be regarded as limitations upon the scope of the invention except in so far as included in the accompanying claims.

We claim:

1. A perspiration retarding or inhibiting composition obtained by combining a soluble astringent salt of a polyvalent metal with a proportion of a water-insoluble metallic base in an amount of from about 4% to about 15% on the soluble astringent salt.

2. A perspiration retarding or inhibiting composition obtained by combining about 10% to about 25% of a soluble astringent salt of a polyvalent metal with from about 1% to about 3% of a water-insoluble metallic base.

3. A perspiration retarding or inhibiting composition obtained by combining about 10% to about 25% of a soluble astringent salt of aluminum with from about 1% to about 3% of a water-insoluble metallic base.

4. A perspiration retarding or inhibiting composition obtained by combining about 10% to about 25% of a soluble astringent salt of zinc with from about 1% to about 3% of an insoluble metallic base.

5. A perspiration retarding or inhibiting composition obtained by combining about 10% to about 25% of a soluble astringent salt of iron with from about 1% to about 3% of an insoluble metallic base.

6. A perspiration retarding or inhibiting composition obtained by combining in a water-containing vehicle, a soluble astringent salt of a polyvalent metal and a proportion of a water-insoluble basic aluminum compound in an amount of from about 4% to about 15% on the soluble astringent salt.

7. A perspiration retarding or inhibiting composition obtained by combining in a water-containing vehicle, a soluble astringent salt of a polyvalent metal and a proportion of a water-insoluble basic zinc compound in an amount of from about 4% to about 15% on the soluble astringent salt.

8. A perspiration retarding or inhibiting composition obtained by combining in a water-containing vehicle, a soluble astringent salt of a polyvalent metal and a proportion of an insoluble basic magnesium compound in amount from about 4% to about 15% on the soluble astringent salt.

9. A perspiration retarding or inhibiting composition obtained by combining in a water-containing vehicle, a soluble astringent salt of aluminum and a proportion of a water-insoluble basic aluminum compound in an amount of from about 4% to about 15% on the soluble astringent salt.
